DISPOSABLE CIGARETTE LIGHTER

Robert Hocq, Boulogne-Billancourt, France, assignor to Societe Franco-Hispano-Americaine Francispam, Paris,
France

Filed Dec. 9, 1968, Ser. No. 14,852
Claims priority, application France June 10, 1968

Term of patent 14 years

Int. Cl. D27—05

U.S. Cl. D48—27

FIG. 1

FIG. 2

FIG. 3

FIG. 4

FIG. 5

FIG. 6

FIG. 1 is a plan view showing the bottom of a disposable cigarette lighter showing my new design;

FIG. 2 is an elevational view of the back of this cigarette lighter;

FIG. 3 is an elevational view showing one side of this lighter;

FIG. 4 is an elevational view showing the front of this lighter;

FIG. 5 is a plan view showing the top of this lighter; and

FIG. 6 is an enlarged perspective view showing the top, the front and one side of the lighter.

The side of the lighter opposite to the side shown in FIG. 3 is identical to the side shown therein.

I claim:

The ornamental design for a disposable cigarette lighter, substantially as shown and described.
